Henry Beebe
Letters Patent

The Schedule referred to in these Letters Patent and making part of the same containing a description in the words of the said Henry Beebe himself of his improvement in the construction of wheels for the use of all kinds of carriages

To all to whom these presents shall come. Be it known that I Henry Beebe of the Town of Harrington, in the County of Rockland and State of New York have invented a new and useful improvement in the construction of wheels for the use of all kinds of carriages such as stages, waggon carts, gigs coaches, road cars and other kinds of transportation vehicles which invention he calls "The metallic vehicle circular wheel" and that the following is a full and exact description of the construction and operation of the said machine as invented or improved by me. The wheel to consist of the hub, spokes, rim and tire with such other appendages thereto as are hereinafter mentioned. The spokes and the rim to consist of wrought or malleable iron or steel the hub of the cast iron, brass composition of metal or of any metallic substance. The tire of wrought or malleable iron, brass with or without steel. The rim of the wheel to be circular of such diameter as the constructor may choose and as may be appropriate to the use for which it is intended. If the wheel is to be of the diameter of four feet and one half the thickness of the rim should be about five sixteenths of an inch and the width about one inch and three eighths. This rim to be made by bending the bar of the material of which it is to be made into a circular and fastening the two ends by welding, or otherwise at the option of the constructor or the rim may consist of segments or petals. Either before or after the rim is formed it is to be pierced with a many holes as the same intended to be given to the wheel, twelve or fourteen more or less at the option of the constructor, these holes to be equidistant from each other and to be in the middle of the rim and of such size, as may be deemed sufficient regard being had to the use intended to be made of the wheel, to the size of the wheel and the materials

end of the spokes and running for the reception of the spokes. The spokes to be made of a length adapted to the size of the rim to be of solid or hollow iron or steel. Either round or otherwise as may suit the construction on one end of each spoke is to be cut a slot and a nut put on the same; the end of the spoke on which is to be cut the slot is to be of a size to fit the hole to be cut in the rim; the ends of the spokes to be inserted in the holes in the rim keeping the nuts on the outside of the rim. After the spokes are thus inserted in the rim the hole is to be placed on a form for receiving the hub. A pattern of wood or other material is to be made for the hub of the form and dimensions adapted to the size and strength of the intended wheel and of the appropriate proportion on the outside with the addition of the core points which are to be of the size of the intended hole at each end of the hub. The pattern is then to be divided into as many parts as the number of spokes intended for the wheel. Holes are then to be made in the pattern for receiving the other ends of the spokes to be of suitable size and depth for the spokes and hub. The pattern is then to be sawed into two parts through that part of the hole intended for the centre of the spokes, then place the pattern in the centre of the wheel or rim with a screw passing through the centre of each core point with a nut on the outside side so as to be drawn when the wood is made for the hub. The mould for the hub is then made on the pattern after which the screw is drawn and the upper part of the wood and pattern is broken leaving the ends of the spokes which enter the pattern and the hub. Half of one then the rim is drawn from the form with the spokes. Then the under part of the pattern is drawn from the under part of the mould. Thus the mould for the hub is completed ready to receive the concrete side forms the outside of the hub for the reception of the axle box. The shape of the core is to be such as may be necessary for the hub of the inside of the hub to be of a taper fitted for the axle box and to be of a shape to make a hollow in the hub between the bays comprising, a neck as may be to the bridge on the outside of the hub. The object and use of which is to provide a receptacle for the oil or grease for the wheel and to distribute the weight of the hub. The hub may be formed with or without the hollow or receptacle.

acceptable. The cores to be placed in the punts or moulds in its appropriate position for forming the inside of a hole through the hub and the rim and spokes are then to be placed in the moulds or punts as when mounted when the flesh is to be closed. The metal of which the hub is to be made is forced in into the moulds or punts and thus the hub is formed. The rim spokes and hub have to be removed and freed from the sand and the core removed, then a centre piece of wood or any other material to be put through the hole in the hub made for the axle-tree on which pin turn the wheel thus formed to discover if the rim be true with the centre of the hub, turn the nut on the ends of the spokes on the inside of the rim snug up to the rim and if the rim be not true with the centre of the hub turn the nut so as to push out the rim to make it true, the ends of the spokes which are inserted in the rim to pass quite through it after the rim is made true to the centre of the hub after the rim is made true the ends of the spokes which pass through it are to be made even with the outside of the rim by cutting them off or filing them down of they project beyond it. The tie of the hub is made of a bar of iron wrought or malleable laid with steel or not at the option of the controller and formed to fit the outside of the rim above described as to width and diameter and to be of such thickness as the controller may choose. The tie is made hot and while hot fasten to the rim and then cooled by water so as to make it light on to the rim and spokes, it may be further secured on to the rim and spokes by bolts passing through the tie and rim between the spokes in such number as may suit the controller. These bolts may be made to go clear through the rim and have heads down on the inside or have a cap on the end of each inside the rim with a nut, research end of the bolts may be fitted with a band of wrought or malleable iron if the controller shall see fit in order to protect the ends of the bolts. The rim of the wheel outside of being made of iron may be made of wood at the option of the controller or in the necessary cases iron in iron making streets. The invention hereby claimed and desired to be secured by letters patent consists of the whole of the machine or wheel above described when taken together.

J. H.
the mode and manner of constructing the same, particularly the principle
of constructing the hub upon the rim or steel spokes. But no claim is
made for the mode of making the hub, the spokes, the rim or the tie
or any of the parts of the wheel or machine taken separately.
For a further illustration of my invention I refer to the model and
drawing of the same deposited in the Patent Office. In testimony
whereof I have caused to subscribe my name this twenty-first day of
February one thousand eight hundred and thirty-four
